CORE FOR THREAD OR YARN PACKAGES

Lawrence B. Stegner, Hartsville, S. C., assignor
to Sonoco Products Company, Hartsville, S. C.,
a corporation of South Carolina

Application November 4, 1933, Serial No. 696,734

2 Claims. (Cl. 242—119)

This invention relates to cores for thread packages, that is, to articles intended for use in the textile trades for centrally supporting thread windings or packages during the formation of

5 such windings, transportation of the same, and final unwinding upon a machine for the fabrication of cloth by knitting or weaving processes.

The invention contemplates the provision of a core of this type which is designed particularly 10 for use in connection with winding machines. In such a machine a thread of great length, equal for instance to the combined lengths of the threads wound upon a plurality of bobbins, is wound into the form of a relatively large cylindrical package, commonly known as a "cheese." During the winding of such package upon a core of the type contemplated in the present invention, the core is supported for revolution about its own axis upon a freely revoluble carrier member.

20 When the package is completed or has reached the desired size, this core, with thread package thereon, is slipped off of the carrier and is ready for transportation to a warping machine or other textile unit.

25 Heretofore thread cores of this general type have been fabricated of metal, bakelite, or other expensive materials, and it has not been deemed commercially feasible to ship or transport thread packages from mill to mill owing to the relatively 30 large investment in the core itself, large numbers of which would necessarily have to be used with each winding machine were the product of that machine shipped substantial distances. Heretofore economy has required that the numbers of 35 cores used and each winding machine be minimized, and this in turn has necessitated retention of the cores at the plant where the winding operations are carried out.

In accordance with the present invention, however, 40 a thread core is provided which may be produced at a minor fraction of the cost of production of cores of the type heretofore used, which permits the use, with economy, of many more cores per winding machine, enabling the operator of the machine to ship his thread windings or packages, duly mounted upon cores, for long 45 distances. In fact thread cores of the type contemplated by the present invention may be fabricated at such low cost that they may be used only once and thereafter discarded, thus making it possible for a knitter or weaver located at one point to buy thread packages fabricated at a distant point and to furthermore hold in stock at his own plant any desired quantity of such packages, the cost of the core adding only an insig-

nificant amount to the cost of the package. After the thread is unwound from the novel core, it may be discarded if desired without appreciable loss.

In connection with plants having winding machines and also provided with fabricating machines sufficient in number to utilize the entire output of the winding machine, it may be economically advantageous to repeatedly use the thread cores, and wherever such reuse is to be practiced, the paper cores contemplated by the present invention may be subjected to a hardening process whereby the core is made stiffer and well able to withstand impacts which it necessarily meets with in such repeated use.

In addition to the great advantage of reduced cost, thereby permitting wider usage, the core in and of itself has many advantages over similar devices of the prior art. It is light in weight, being very considerably lighter than metal or 20 bakelite cores of the type heretofore most commonly used. It furthermore possesses superior yarn retaining qualities whereby a thread or yarn package is caused to cling tightly thereto during both winding and unwinding operations and 25 during shipment. It is attractive in appearance and more convenient for the mill operator to handle by reason of its lighter weight and roughened surface. Still other advantages of the invention will be apparent to those skilled in the art.

In the accompanying drawing, two forms of the improved core are disclosed by way of example. It will be appreciated that in its minor details the core may be considerably varied in design and construction in adapting the same to 35 winding machines of various types.

In the drawing:

Figure 1 is an axial section through one form of improved core, showing the same to be mounted upon a revoluble holder of a winding machine 40 and showing a thread winding thereon;

Figure 2 is a side elevation of the same thread core, with package removed, partly broken away to show details of construction;

Figure 3 is an axial section through a slightly 45 modified type of thread core constructed in accordance with the invention; and

Figure 4 is a section on line 4—4 of Figure 3.

The member indicated at 10 in Figure 1 of the drawing is the swinging arm of a winding machine, and the cylindrical member 11 comprises a holder for the thread core, this member being supported by the arm 10 for free revolution about an axis normal to the arm. Elements 10 and 11 just described form no portion of the present 55

invention and may vary considerably in design and arrangement of parts. It may be said, however, that member 11 is provided with a thread core retaining device which, in this instance, includes ball members 12 normally pressed by springs (not illustrated) so as to project outwardly through apertures 13 formed in the cylindrical surface of revoluble holder 11. These ball members in reality comprise yieldable detents adapted to interlock with the thread core and to prevent accidental axial sliding movement of the thread core on member 11, but which members yield when any appreciable force is exerted on the thread core tending to move it axially of the holder 11 and to thereby release the holder. A typical thread package of the cylindrical type is indicated at 14.

The thread core shown in Figure 1 is also illustrated in Figure 2 but in greater detail. It comprises an inner section, indicated generally at 15, and an outer cover, indicated at 16. The inner section is built up of a plurality of concentric paper cylinders secured together by a suitable adhesive so as to form a single, unitary, compact, and relatively stiff and strong supporting cylinder. The paper of which these individual cylinders is fabricated, while not of high quality or great cost, is relatively dense and smooth so that the resulting cylinder has considerable mechanical strength. The cover 16 for the inner section of the core is preferably of relatively soft embossed paper so that the inner windings of the thread package supported by the core tend to cling to its surface.

While the core as thus far described may be fabricated by various methods, I prefer to form the inner section 15, which, as previously explained, comprises a plurality of concentric cylinders secured together, by spirally winding a plurality of paper strips upon a cylindrical mandrel, one upon the other, and thereafter severing the relatively long tube thus formed into proper core lengths. Each of the cylinders which come over the inner structure 15 may therefore be said to comprise a single sheet of paper, the meeting edges of which abut along a line spirally disposed with respect to the axis of the core. The several sheets are so arranged that the joint between the edges of each is covered by an unbroken surface on the next adjacent sheet, this method of breaking joints insuring that the inner structure has a maximum strength for the weight of paper employed in its construction. The outer layer 16 of paper is applied immediately after the formation of the inner structure and is wound convolutely instead of spirally, its edges meeting along a line parallel to the axis of the core. Preferably the meeting edges of the paper sheet 16 are mutually chamfered or beveled so that no ridge is formed along the line of meeting.

After the application of the covering sheet 16, the paper core is subjected to two further operations. In one operation it is revolved relatively to a tool inserted in its interior, which exerts a very considerable outward pressure against the inner surface of the core, this relative rotation of tool and core continuing until a very substantial groove, indicated at 17, is formed interiorly thereof, the paper body displaced in the formation of the groove appearing exteriorly of the otherwise cylindrical exterior surface of the core so as to form a rib 18. One annular end of the core is then upset or deformed, preferably by pressing the end surface against an annularly grooved and rapidly rotating die, this operation being con-

tinued until the end of the core is deflected inwardly as shown in Figures 1 and 2, the end surface 19 being preferably turned to lie in a plane transverse of the axis of the core, as shown.

When in use, the inturned end of the core constitutes a means not only for insuring that the core is applied to the holder 11 by movement in one direction only, but it also constitutes a stop limiting the movement of the core onto the holder and thereby preventing the opposite end of the core from coming in contact with the arm 10 which would naturally frictionally retard rotation of the holder relatively to the arm. The provision of a stop such as indicated also insures that the core will be so positioned on the holder that the retaining members 12 will exactly engage within groove 17.

In the manufacture of the form of spool disclosed in Figures 3 and 4 of the drawing, substantially the same series of operations are carried out. An interior structure comprising a series of concentric paper cylinders is indicated at 20, and a covering sheet of roughened or embossed paper, indicated at 21, is affixed thereto. In the case of this core, however, no external rib 25 is formed, the groove 22 being formed either by simply compressing the paper by a suitable tool or by removing a portion of the same by a grinding tool. In addition a plurality of circular holes, one of which is indicated at 23, are formed in the 20 wall of the core, these holes opening into the bottom of the groove 22. The spring-pressed members 12 may enter these holes when the core is placed upon a holder such as 11, thus providing additional interlock between the core and holder. 35 Instead of inturning the end of the core as in the case of the invention first described, minor sections of the same adjacent one end are displaced by stamping or punching operations, four interiorly projecting tabs or deformed portions 24 being thereby formed. The inner edge surfaces 24' of these portions 24 comprise abutment surfaces which strike the outer end of holder 11 when the core is placed on the holder, thus limiting its movement and insuring proper interlocking of 45 the detents 12 with the core and preventing the end of the core from striking the arm 10.

As has been before explained, cores fabricated in accordance with the invention may be subjected, if desired, to the action of a hardening 50 compound; for instance, they may be impregnated with sulphur after being otherwise completely formed and, when so treated, attain great hardness, thus enabling them to be used many times. If, however, the novel paper cores are 55 intended for a single use only, as where it is intended that they shall be shipped with thread packages thereon from one plant to a distant plant, hardening in this manner is quite unnecessary, a paper core formed as described being well 60 able to withstand the impact and shock incident to transportation without damage. By placing the surface covering on the inner structure as a convolute winding, it acts as a substantial retaining layer for the outer paper cylinder of the 65 inner structure, preventing loosening of the tapering corners of the sheet which comprises this layer. Were the covering sheet 16 omitted, one or other of the pointed ends of the spirally formed 70 outer layer of the inner structure might become loosened in use, thus providing an upward projection which might be caught by the thread with resulting damage or breakage to the thread.

Having thus described the invention, what is 75

claimed as new and desired to be secured by Letters Patent is:

1. A cylindrical paper core for a yarn package having spaced inwardly distorted portions adjacent one end thereof, said portions comprising stop means to limit the movement of the core onto a cylindrical core holder.

2. A cylindrical paper core having a groove formed interiorly thereof, in a transverse plane, and a plurality of apertures formed in the bottom of said groove and extending through the wall of the core.

LAWRENCE B. STOGNER.
